UNITED STATES PATENT OFFICE.

LAZARD KAHN, OF HAMILTON, OHIO, ASSIGNOR TO THE HARRIS STOVE PATTERN AND MACHINERY COMPANY, OF SAME PLACE.

DESIGN FOR A STOVE.

SPECIFICATION forming part of Design No. 16,580, dated March 23, 1886.

Application filed January 23, 1886. Serial No. 158,340. Term of patent 7 years.

To all whom it may concern:

Be it known that I, LAZARD KAHN, of Hamilton, Butler county, Ohio, have invented and produced a new and original Design for Stoves, 5 of which the following is a specification, reference being had to the accompanying photograph, which exhibits the newly-designed stove in perspective.

My design relates to stepped-top stoves; and 10 the distinguishing feature of the design rests in door-panels whose grounds present granular roughenings with inner margins in the form of rectangular panels.

In the illustration, A indicates the stepped 15 top of the stove; D, the panel-grounds of the

side doors thereof, such grounds presenting the aspect of granular roughenings; and E, the inner margin of the doors, such margin consisting of a series of rectangular panels.

I claim as my invention—

The design for a stove consisting of the following particulars, viz: a stepped top, side door having panel-grounds presenting the aspect of granular roughenings, and inner door-margins consisting of a series of rectangular 25 panels, all combined as shown.

LAZARD KAHN.
